UNITED STATES PATENT OFFICE.

FRANZ KUHLO AND CARL ECKER, OF BERLIN, GERMANY; SAID ECKER
ASSIGNOR TO SAID KUHLO.

CIRCUIT CLOSING AND INTERRUPTING DEVICE.

SPECIFICATION forming part of Letters Patent No. 638,020, dated November 28, 1899.

Application filed May 17, 1899. Serial No. 717,141. (No model.)

To all whom it may concern:

Be it known that we, FRANZ KUHLO and CARL ECKER, subjects of the King of Prussia, German Emperor, and residents of Berlin, 5 in the Kingdom of Prussia, German Empire have invented a new and Improved Circuit Closing and Interrupting Device, (for which a patent was applied for in Germany on the 23d of November, 1898,) of which the following is an exact specification.

The present invention relates to a circuit closing and interrupting device; and it consists, essentially, of a mechanism by means of which a spring is put under tension when the 15 circuit is closed, the said spring acting to interrupt the circuit when a certain volume of a liquid body has been sucked through a small opening.

Our invention will be the better understood 20 with reference to the accompanying drawings, in which—

Figure 1 represents a vertical section through our device. Fig. 2 is a horizontal section on line $x-x$ of Fig. 1.

25 R is a metallic tube, the upper side walls of which are diminished somewhat in thickness. This tube R is filled with glycerin, oil, or a similar body up to the height h , where the thickness of the wall of the cylinder is diminished.

30 Within this tube R slides a piston K, of slightly-smaller diameter than the tube itself. The piston-rod of this piston K is guided through a piece of caoutchouc H, arranged at the top of the tube R, and carries at its up- 35 per extremity a knob or button D. Between the button D and the caoutchouc piece H a spiral spring S is inserted, so as to surround the piston-rod. A spring F, in form of a clamp, is fixed to the lower surface of the but- 40 ton and presses against the caoutchouc piece H. The piston K is illustrated in Fig. 2 of the drawings and, as clearly to be seen, is provided with perforations d , closed by a cover p , arranged at the upper side of the 45 piston, and held down by a small spring p' , so that the oil can flow through the perforations only from the lower side to the upper side—namely, the oil flows through these perforations when the piston is pressed down.

50 The working of the apparatus is as follows:

When the knob D, and consequently the piston K and the spring F, is pressed down, the latter presses against the side walls of the tube R. When now one pole of the circuit is connected to the clamp F and the other pole to the metallic tube R, the circuit is closed as soon as the spring F is in contact with the metallic tube R. The piston K descends and the oil is pressed through the perforations and accumulates above the piston. Owing to 60 the pressure of the spiral spring S, which now is put under compression, the oil slowly is sucked downward through the small space between the walls of the piston and the tube. At the moment when the last drop has passed 65 through this space, the piston having reached the height h , the air, owing to the larger diameter of the tube R, quickly passes through and the piston, owing to the pressure of the spiral spring S and of the air underneath, 70 rapidly is pushed against the caoutchouc piece H. This rapid rising of the piston effects the sudden interruption of the circuit.

Evidently the time for which the circuit is closed depends upon several circumstances— 75 for instance, upon the size of the tube R, and consequently the quantity of oil employed, the strength of the spiral spring S, and the amount of the space through which the oil flows downward again.

The present device can be cheaply constructed and will be found to work for a long period of time.

The interruption of the current takes place in an effective manner, for the reason that 85 the air quickly passes beneath the piston, owing to the diminished thickness of the side wall of the tube R, and, together with the pressure of the spiral spring, the piston rapidly is pushed upward, thus the circuit being in- 90 interrupted.

Having thus fully described the nature of this invention, what we desire to secure by Letters Patent of the United States is—

In an apparatus for closing and interrupting circuits, the combination with a metallic tube R forming one pole of the circuit and filled with oil to a certain height and having side walls which at the upper part are diminished in thickness, a caoutchouc piece 100

II closing the tube R, a piston K sliding within this tube and leaving a space between the side walls of the tube R, perforations *d* provided in the piston, a cover *p* closing these 5 perforations and acting like a valve, a spiral spring S surrounding the piston-rod of the piston K and reposing upon the caoutchouc piece II, a clamp-formed spring F forming the other pole of the circuit and pressing 10 against the caoutchouc piece, to be pressed

downward, for the purpose and substantially as set forth.

In witness whereof we have hereunto set our hands in presence of two witnesses.

FRANZ KUHLO.
CARL ECKER.
